UNITED STATES PATENT OFFICE

ALVA G. LITTLE, OF DENVER, COLORADO

DESIGN FOR A DISPLAY DEVICE

Application filed January 26, 1931. Serial No. 38,448. Term of patent 14 years.

To all whom it may concern:

Be it known that I, ALVA G. LITTLE, a citizen of the United States, residing in the city and county of Denver, State of Colorado, have invented a new, original, and ornamental Design for a Display Device, of which the following is a specification, reference being had to the accompanying drawing, forming part thereof.

The design consists of a base supporting a series of piles of boxes adapted to contain rolls of wall paper, one box leaning against the front of each pile, each box having its front face decorated with pictorial representations of the wall paper design contained therein, and each box having a handle on its top edge.

The combination of the several elements above described constitute a single unitary article.

I claim:

The ornamental design for a display device as shown and described.
